(57) **CLAIM**

The ornamental design for a handheld garment steamer, as shown and described.

DESCRIPTION

FIG. 1 is a front right side perspective view of an ornamental design for a handheld garment steamer according to the present invention;

FIG. 2 is rear left side perspective view of the handheld garment steamer of FIG. 1;

FIG. 3 is a front elevational view of the handheld garment steamer of FIG. 1;

FIG. 4 is a rear elevational view of the handheld garment steamer of FIG. 1;

FIG. 5 is a right side elevational view of the handheld garment steamer of FIG. 1, and the view of the handheld garment steamer that is rotated 180 degrees from FIG. 5 is a mirror image of FIG. 5;

FIG. 6 is a top plan view of the handheld garment steamer of FIG. 1; and,

FIG. 7 is a bottom plan view of the handheld garment steamer of FIG. 1.

The broken line shown in the drawings are for the purpose of illustrating environmental structure and forms no part of the claimed design.
